JAR COVER WRENCH

Joseph J. Panik, Detroit, Mich.

Application September 24, 1948, Serial No. 50,903

9 Claims. (Cl. 81—3.44)

1

This invention relates to clamping devices and, in particular, refers to an improved clamping device adapted to serve as a wrench or tool for loosening and tightening the covers of jars and the like.

The need for a suitable mechanical device to assist in the tightening and especially the loosening of jar covers is well known. While tools for this purpose have been proposed in the past, they have for various reasons been impractical or unsatisfactory so that at the present time it is still necessary to resort to various makeshift expedients when attempting to remove unyielding covers.

It is thus an object of the present invention to provide a household implement which will expedite the tightening and removal of jar covers or the like.

An additional object is to provide a tool which does not have to be manipulated by the hands of one attempting to cap or decap a jar thus enabling the user to grasp the jar with both hands.

A further object is to provide a decapping tool which is adapted for use with a wide range of cover sizes.

Other objects and novel features of the invention will become apparent upon consideration of the accompanying drawings in which:

Fig. 1 is a bottom plan view of a preferred embodiment of the invention;

Fig. 2 is a front elevation of the device shown in Fig. 1;

Fig. 3 is a top plan view of the device shown in Fig. 1 and showing the jaws at the outward limit of their longitudinal movement; and,

Fig. 4 is a cross section through the device as taken on line 4—4 of Fig. 1 and shows a jar cover engaged by the gripping members.

Referring to the drawings, the improved decapping tool has a platelike frame 1 which is provided with an upstanding marginal edge 3 and screw holes 5 whereby it may be attached to the underside of a cupboard or the like with a surface of the frame 1 spaced from the cupboard and facing downwardly.

A pair of gripping members 7 are provided, which may have coacting arcuate cover engaging jaw portions 8 internally faced with relatively resilient pads 10 of rubber or the like and which may be serrated as shown to increase the effectiveness of their gripping action. The gripping members are pivoted together at one end, as shown at 9, and are connected to the frame 1 for movement relative thereto in a longitudinal direction. For this purpose the frame 1 has a

2

slot 11 which receives the pivot pin 9. A clip 13 is suitably affixed to the end of the pin 9 whereby the jaws 7 are slidably clamped to the frame 1. A tension spring 15 is attached to the clip 13 and to a suitable point 16 on the frame 1 for yieldably urging the jaws 7 to a position wherein the pin 9 is seated in the inner end of the slot 11.

The frame plate 1 is provided with a transverse slot 17 through which the leg portions 19 of the jaws 7 extend to the other or topside of the frame. Outwardly extending links 21 are pivoted to the legs 19 as shown at 23. The other ends of the links 21 are connected to the frame 1. This may be a direct pivotal connection or, in order to facilitate the initial adjustment of the jaw members, may be made through the structure which is best illustrated in Fig. 3.

As shown in Fig. 3, the links 21 are pivotally connected to the ends of a pair of bell cranks 25 and 27 by means of pins 29 and 31, respectively. The bell cranks are pivoted at their central sections to the frame 1, as shown at 33, and are pivotally joined together by a pin 35 which may move in a suitable slot 37 provided in one of the bell cranks. One end of the pin 31 is threaded and extends through an arcuate slot 39 in the plate 1, this slot being formed on an arc of a circle having the pivot 33 of the bell crank 25 as a center, to the other side where it threadedly receives a wing nut 41. A spacer 43 may be inserted between the link 21 and the plate 1 as shown in Fig. 2.

In normal household use, the plate 1 is affixed, through the medium of screws extending through holes 5, to the underside of a cupboard or other suitable support so that the jaw edges 8 extend downwardly, i. e. a position which is inverted from that shown in Fig. 4. Alternatively, the device may be attached to a vertical wall or other surface at a convenient height, with the jaws 7 extending upwardly. The spring 15 holds the jaw members 7 against the inner end of the slot 11 and the size of the jaw opening is adjusted to the jar cover diameter by means of the wing nut 41 and pin 29. The wing nut 41 is unloosened so that the end of bell crank 25 and the link 21 are unclamped from the plate 1. Assuming that the jaws 7 are spread to a maximum opening, the jar cover is inserted in the jaws 7 and the nut 41 and pin 29 moved inwardly in the slot 39. This movement pivots bell crank 25 about the pin 33 so that the pivotal connection 35 between the bell cranks 25 and 27 moves toward the slot 11. This pivots the bell crank 27 so that its pivot pin 31 moves inwardly an amount

equal to the inward movement of the pin 29. The pins 29 and 31 act through the links 21 to move the jaws 7 toward each other about pivot point 9. This movement is continued until the jaw pads 10 contact the opposite sides of the cover, whereupon the wing nut 41 is tightened on pin 29. This clamps the bell crank 25 and the link 21 directly to the plate 1 and since the bell crank 25 is thus rendered immovable the bell crank 27 is likewise held in fixed position so that the pin 31 is incapable of movement. The initial size of the opening between the jaw pads 10 is therefore fixedly adjusted.

With the initial adjustment made and the cover inserted between the jaw edges 8, the jar A is bodily translated in a longitudinal direction outwardly or to the left in Fig. 4 (upwardly in Fig. 1). This forces the jaws 7 to move longitudinally in the slot 11 against the resistance of spring 15. This movement causes the links 21 to pivot about their fixed pivot points 29 and 31. It will be recognized that in the normal biased position of Fig. 1, the pivot pins 23 connecting the links 21 and the jaws 7, are on the far side of center with respect to their fixed pivot points 29 and 31 and the slot 11. Thus, when the jaws 7 are moved against the resistance of the spring, the points 23 pivot inwardly carrying with them the jaws 7 which pivot about pin 3. This inward movement of the jaw members 7 toward each other causes the jaw edges 8 to clamp the edge of the jar cover A with great force, the pads 10 being compressed to tightly grip the cover, so that when the jar is twisted manually the cover remains stationary and is thus loosened or tightened, as the case may be.

It is desirable that the links 21 pass over center before the jar is twisted so that a positive lock is provided to prevent expansion and loosening of the jaws 7 due to the applied turning forces on the jar A. It will be recognized from the drawings that this is accomplished by making the slot 11 of sufficient length so that this is possible. Passage over center despite the tight grip previously placed on the jar cover by the jaws 7 is permitted by the resilient character of the pads 10.

After the jar cover has been loosened or tightened, longitudinal forces is exerted on the jar A in the opposite direction to move the links 21 back over center. This movement acts in a manner which is now apparent to enlarge the jaw opening and allow the jar A to be withdrawn.

It will be recognized that various modifications, omissions and additions may be made to the structure herein described, without departing from the spirit of the invention.

What is claimed is:

1. A clamping device comprising a frame, a pair of coacting jaw members mounted on said frame for joint longitudinal movement and for transverse movement relative to each other, said jaw members being adapted to receive a body to be clamped and to be longitudinally moved relative to the frame by translation of said body, and means connected to the frame and coacting with a jaw member whereby longitudinal movement of the jaws in one direction causes a jaw to move toward the other jaw.

2. A clamping device comprising a frame adapted to be fixed in a stationary position, gripping means, means connecting the gripping means to the frame but permitting longitudinal movement relative thereto, said gripping means including elements movable in a direction trans-

verse to said longitudinal movement to expand and contract said aperture, and linkage connecting the gripping means to the frame and adapted to transversely move said elements upon longitudinal movement of the gripping means.

3. The invention as claimed in claim 2 wherein said linkage includes a toggle link that is arranged to pass over center upon longitudinal movement in one direction whereby expanding forces on the gripping means are rendered ineffective.

4. The invention as claimed in claim 3 wherein the gripping means includes means providing resilient surfaces thereon for engagement with a body to be clamped.

5. A clamping device comprising a frame adapted to be fixed in a stationary position, gripping means providing an aperture to receive an article to be clamped, means connecting the gripping means to the frame for longitudinal movement relative thereto, said gripping means including elements movable in a direction transverse to said longitudinal movement to expand and contract said aperture, means connected to the frame and to the gripping means operable upon longitudinal movement of the gripping means for transversely moving said elements to expand and contract the aperture, and adjustable means for fixedly connecting the elements to the frame and therefore controlling the position of the elements and thus the initial size of the gripping means within predetermined limits.

6. A decapping tool for jars and the like comprising a frame, a pair of coacting jaw members pivoted to the frame and adapted to receive a jar cover, said jaw members being pivoted to a jaw member pivot that is slidably mounted on the frame whereby the jaw members are capable of longitudinal movement upon the application of translatory forces to jar covers received thereby, a pair of bell cranks pivotally connected at their central pivot points to the frame, non-binding pivot means interconnecting the bell cranks at one end, links pivotally connecting the other ends of the bell cranks to the respective jaw members, said links passing over center as a result of a pre-determined amount of longitudinal movement of jars being decapped, and means fixedly connecting said other end of one of the bell cranks to the frame, said last means being capable of lateral adjustment on the frame whereby to provide means for adjusting the initial opening of the jaw members.

7. A tool for tightening or loosening jar covers or the like comprising a frame having means whereby it may be immovably affixed to a stationary member, a pair of jaws adapted to grip a cover, a slidably pivot connecting the jaws to the frame for pivotal movement toward or away from each other and for translatory movement, and means connected to the frame and to the jaws at points spaced from said pivot and operative upon translatory movement of the jaws for pivoting them toward each other whereby, upon insertion of a jar cover into said jaws and then translation of the jar to translate said jaws, the jaws grip the cover so that upon rotation of the jar the cover is held in fixed position and is tightened on or unloosened from the jar.

8. A tool for tightening or loosening jar covers or the like comprising a frame having means whereby it may be fixedly mounted in a stationary position, cover gripping members mounted on the frame and defining an aperture to receive a cover, said members being movable in

directions to expand or contract said aperture, said members also being movable in directions transverse to said expanding and contracting movement, and means connecting the members to the frame and operative upon movement of the members in said transverse directions to simultaneously effect expanding or contracting movement of the members whereby a jar may be grasped with both hands and its cover inserted in the aperture and upon transverse movement of the jar the jaws grip the cover so that both hands may be used to twist the jar to tighten or loosen the cover.

9. A decapping wrench for jar covers comprising a platelike frame having means whereby it may be affixed to a cupboard or the like, said frame having an elongated slot, a member attached to the frame and slidable in said slot, a pair of arcuate jaws defining a cover receiving aperture, said jaws being pivoted to said member whereby they are capable of pivotal movement relative to the frame and of translation relative to the frame upon sliding of the member in the slot, said slot being directed radially of the aperture provided by said jaws, said jaws each having

10

15

20

25

a leg extending generally parallel to said slot and on the opposite side of said cover receiving aperture, a pair of links each extending transversely to a jaw leg and pivoted thereto, the other ends of said links being pivoted on a fixed axis to the frame whereby said jaws move transversely as well as longitudinally when said member slides in said slot.
